UNITED STATES PATENT OFFICE.

ATTILIO BIANCHI AND JOHN OCCHIPINTI, OF NEW YORK, N. Y.

MACHINE FOR AFFIXING FABRIC COVERINGS.

1,302,288.

Specification of Letters Patent. Patented Apr. 29, 1919.

Application filed January 19, 1918. Serial No. 212,818.

To all whom it may concern:

Be it known that we, ATTILIO BIANCHI and JOHN OCCHIPINTI, citizens of the United States, residing at New York, in the county 5 of New York and State of New York, have invented new and useful Improvements in Machines for Affixing Fabric Coverings, of which the following is a specification.

This invention relates to coating machines.

10 In the manufacture of automobiles, carriages, or similar vehicles, it is customary to provide textile material, leather or a substitute for leather, using the same as a facing or coating for swinging doors, the inner 15 walls or panels of the body of the vehicle or other desired parts, whereby to give to the interior of the vehicle, an ornamental and attractive finish. To the best of our knowledge, the manufacturing of such covers or 20 facings, has heretofore been done by hand and is therefore a slow, trying and costly operation, aside from the fact that it is impossible to give to the complete article manufactured, that consistency and uniformity 25 which is necessary to a commercial production thereof.

One of the objects of the invention resides in the provision of means for initially bending or folding the edges of the facing or 30 covering material so that such edges will lie substantially at right angles to the plane of a stiffening sheet with which the material is associated, and then subsequently subjecting the material to the action of a folding 35 mechanism which will operate against the edges thereof and completely fold the same against one side of the stiffening material, causing the latter and the former to be permanently bound together and producing 40 a panel-like article when completed which may be secured against the inner face of a door, a panel or inside wall of a vehicle as and for the purpose set forth elsewhere herein.

45 Another object of the invention is to provide co-acting folding and pressing mechanisms which will operate to permit the stiffening element to be interposed therebetween during the action of folding the marginal edges of the facing or coating material 50 over the edges of said element, and means for effecting relative adjustments of said mechanisms to permit the work to be conveniently associated therewith and removed 55 therefrom.

Another object of the invention resides in

the provision of folding mechanism which will permit of the successive introduction of work thereto and removal of such work therefrom with utmost rapidity and accuracy in a uniform application of one element of the work with another, mechanisms which will be simple of construction, positive of action, and which will permit of a maximum output in a minimum space of time.

In the drawings:—

Figure 1, is a side view of the apparatus.

Fig. 2, is a rear view thereof.

Fig. 3, is a vertical section therethrough. 70

Fig. 4, is a front view of the edge folding mechanism.

Fig. 5 is a vertical section on line 5—5, of Fig. 4.

Fig. 6 is a section on line 6—6, of Fig. 4. 75

Fig. 7, is a plan view of a portion of the apparatus with parts in section.

Fig. 8, is a section taken approximately on line 8—8, of Fig. 7.

Fig. 9, is a detail view of the stop mechanism. 80

Fig. 10, is a side view thereof.

Fig. 11, is a side view of the actuating cam.

Fig. 12, is a section through a part of the 85 edge folding mechanism.

The apparatus comprises two mechanisms 15, and 16, respectively, the former of which will be hereinafter referred to as, "the edge folding and pressing mechanism," and the 20 latter, a work supporting and positioning mechanism. Specifically, the apparatus includes a supporting frame 17, provided with side bars 18—18, a front bar 19, and other minor instrumentalities of minor importance 25 which need not be discussed in that they form no material features of the invention. The upper surfaces of the bars 18—18, extend at a downward and forward angle so as to correspondingly support a rigid bed or 30 table 19', on which the work to be operated upon, is adapted to be placed initially. This bed or table, is connected at its sides with bars 20 and 21, which are mounted to rock 35 at 22, on the frame 17. Crank extensions 23, 100 form integral continuations of said arms and as illustrated, the extension 23, of the arm 20, is provided with a roller 24, which operates in a cam slot 25, in a gear wheel 26. The extension 23, of the arm 21, has a roller 105 27, which operates in a cam groove 28, formed in the inner surface of a gear wheel

29. Both of the wheels 26 and 29, are mounted on a common shaft 30, which is journaled in the frame 17. The cam grooves 25 and 28, are designed whereby on each revolution 5 of the mentioned gear wheels, motion will be imparted to the rockers 20 and 21, so as to respectively raise and lower the table or bed 19', in a manner to be hereinafter described. The work to be operated upon, consists of a 10 stiffening sheet 31, and a covering or facing strip. The former is customarily of cardboard and the latter, textile material or imitation of leather. The size of the stiffening material 31, is such that it normally is fully bound by the sides of the material 32, in order that the marginal edges of the latter can be turned up and then over the marginal edges of the former. Initially, the material 15 31, is secured by an adhesive to the material 32. When the two elements of the work are thus associated with one another, they are placed upon the table or bed 19', so that the material 31, is disposed at the top. Mounted to rock upon the table or bed 19'. 20 25 are pressing shoes 33, which are provided with arcuate surfaces 34, which are adapted to press against the extended edges of the material 32, and fold the same at right angles to the material 31. Any suitable number 30 of these shoes may be employed and in practice, it is found desirable to distribute the same upon the table or bed 19', so that they occupy the relative positions shown in Fig. 7. They are preferably in rows, so that 35 the space between the respective rows will correspond with the shape of the work to be operated upon. In this manner, the arcuate surfaces 34, will be always presented against the extended edges of the covering or facing material 32, and the latter accurately fold with respect to the next adjacent flat side of the stiffening material 31. The stiffening material 31, is substantially of panel configuration and as designed, it is intended for 40 45 application against the inner face of an automobile door or any structure to which an ornamental finish is to be given. We therefore do not wish to be limited to any particular configuration or arrangement of parts 50 as we are principally aiming to bring together only those instrumentalities which are practical and operative for the purpose of binding a comparatively thin sheet of facing or covering material, such as that described 55 with a mating stiffening material, irrespective of the form and shape of the parts to which these materials are to be afterward adopted.

The swinging shoes 33, are normally held 60 distended under the action of suitable springs 35, carried by the table or bed 19'. Beneath the shaft 30, is a power transmitting shaft 35', having a pulley 36, which may be belted to any suitable well known form of motor. 65 At one end, the shaft 35, is provided with a

fixed driving gear wheel 37, arranged in mesh with an idle gear 38, the latter having at one side, a small fixed gear 39, which is in mesh with the gear 26, on said shaft 30. In this manner, power is transmitted to the 70 shaft 30, and is utilized for the purpose of actuating respective mechanisms of the apparatus.

The edge folding mechanism 15, comprises horizontally sliding heads 40, supported by 75 a vertical plate 41, which rises from the frame 17, at the rear thereof. These heads are provided with pins 42, which slide in hollow bosses 43, formed on the plate 41. In these bosses, are springs 44, which operate 80 against the heads 40, to hold the same normally distended. These heads are each provided with a plurality of angularly disposed guides 45 and 46. Rigid folding strips 47, are supported by the heads 40, and the same 85 have end grooves 48, which are received by the respective guides 45 and 46, as shown, and are therefore free to slide thereon. Crank shafts 49, are journaled upon the plate 41, and the same have bevel pinions 50, 90 at their ends. The pinions of the several shafts, mesh with each other so that when power is transmitted to one shaft, it will be continued through all of them. Each shaft is provided with a crank portion 51, having 95 an arm 52, which is connected to the next adjacent strip 47.

As four strips 47, are illustrated, there must consequently be provided, a corresponding number of shafts 49, and in order 100 that these strips can be actuated in pairs, the crank portions 51, of two of said shafts, are extended in an opposite direction to the crank portions of the other shafts. In this manner, two strips 47, will be made to move 105 toward each other while the other strips will be made to move away from each other and vice versa. The area normally defined between the respective strips 47, is slightly greater than the outside area defined by the 110 stiffening element 31, to be operated upon so that when the bed 19', is presented in parallel relation with the plate 41, the angularly turned edges of the facing or covering material 32, will be projected directly in the 115 path of said strips 47, so as to be turned against the opposite face of the stiffening element 31, during operations of said strips 47. The lower shaft 49 is provided at its end with a gear wheel 53, which is in mesh 120 with the gear 29, at times. This gear 29, is of the mutilated type in that the toothed surface thereof extends only a part way around the periphery of said wheel. This is done in order that the parts may functionate 125 as just described. That is to say, there are times when motion will be set up in the gear wheel 53, when the wheel 29, revolves and yet, there will remain another interval when the wheel 53, will be at rest while the wheel 130

29, revolves. The wheel 29, is provided with a cam groove 54, which receives the roller 55, on the rock arm 56, of a locking mechanism 57. This mechanism is operatively supported from the plate 41, and it is provided with a dog 58, which at times, is adapted to engage with the teeth of the gear 53. For this reason, the cam groove 54, is provided with a releasing branch 59, and a setting branch 60, the latter actuating to draw the rocker 56, in a downward direction to advance the dog against the wheel, while the former is designed to operate to elevate the arm 56, and release the dog from said wheel. The groove 28, on the opposite side of the gear wheel 29, and the corresponding groove 25, on the wheel 26, are each provided with a substantially concentric branch 61, and an eccentric branch 62, the former operating to elevate the bed 19', and to maintain an operative position of said bed with relation to the folding strips 47, when the bed is in the position shown in dotted lines in Fig. 1. Subsequent to thus positioning the bed, the dog 58, is released from the wheel 53, in order that motion can be transmitted to said gear 53, and in turn, transferred to the shafts 49. The folding strips 47, will then be operated in the manner described hereinbefore and the covering material will be folded against the opposite side of the stiffening material 31, it being understood that the marginal edges of the facing or covering material have been previously treated to an adhering solution. The stiffening material 31, is provided with an opening 63, which is adapted to receive the shank of a knob of the door to which the finished article is applied. The facing material is slit on radial lines directly at the side of this opening and fingers 64, are produced therein. In order that these fingers can be projected through the opening 63, and properly applied against the opposite face of the material 31, the following instrumentalities are provided:—

A rocker 65, is mounted upon the plate 41. One end of this rocker is provided with a plunger 66, having a semi-cylindrical head 67, and a substantially cylindrical portion 68, the diameter of the latter being greater than the diameter of the opening 63. Sliding in the bed 19', is a spreading plunger 69, which is adapted to be first projected through the opening 63, to arrange the fingers 64, at the opposite side of the stiffening material 31, and spread the same so that when the bed assumes its vertical position where the strips 47, are in position to fold the marginal edges of the facing or covering material, the substantially cylindrical head 67, of the plunger 66, will be projected through the opening 63, and against the plunger 69, while the cylindrical branch 68 will be applied against the fingers 64, to

press the latter against said opposite face of the stiffening material 31. These fingers are of course provided with an adhesive so that under the described action, they will be firmly secured to the rear face of the material 31, described herein. Motion is set up in this rocker 65 by providing a link 70 and connecting said link with a crank portion 71, on the upper shaft 49.

From the foregoing description, it will be observed that if the strips 31, are first associated with the facing materials, the same can be placed in rapid succession upon the bed 19', in order that the marginal edges of the facing or covering materials, will be quickly and uniformly folded over the edges of the stiffening materials. In this manner, the work can be formed expeditiously. The work can be controlled by a single operator and through the niceties referred to, the utmost accuracy in the binding of the elements together, can be relied upon.

The plate 41, is provided with springs 72—72 against which the element 31, is adapted to contact during the edge folding operation. In order to facilitate the folding of the edges of the facing material, the strips 47 are of hollow formation and are adapted to be arranged in communication with a hot water supply source through suitable piping 73. The head 67, is heated in a similar manner by inclosing the same in a hot water jacket 74.

We do not wish to limit ourselves to the exact details of construction described herein, and desire to reserve the right to depart therefrom to all permissible extent within the scope of the appended claims.

What is claimed as new is:—

1. Apparatus for covering a stiffening material with a facing material, comprising a bed upon which the materials are adapted to be supported superposed with the edges of the facing material projecting beyond the edges of the stiffening material, yieldable means on the bed for disposing the edges of the facing material at an angle to the body of the stiffening material and for holding the material on the bed, and a folding mechanism co-acting with the bed to fold said angularly disposed edges of the facing material over and against the opposite side of said stiffening material.

2. Apparatus for covering a stiffening material with a facing material, comprising, a bed upon which the materials are adapted to be supported superposed with the edges of the facing material projecting beyond the edges of the stiffening material, means for bending the edges of the facing material at right angles when said materials are placed on the bed, a folding mechanism, and means for causing the bed to be actively presented to the folding mechanism, the said folding mechanism including pairs of end and side

members for operating against the edges of the facing material whereby to fold the same over the edges of the stiffening material and against the opposite side thereof, and means 5 for moving the members of the side pair toward each other and then the members of the end pair toward each other after the side members have been withdrawn.

3. Apparatus for covering a stiffening material with a facing material, comprising, a bed upon which both materials are adapted 10 to be supported superposed with the edges of the facing material projecting beyond the edges of the stiffening material, yieldable 15 means for gripping both materials and for confining the same temporarily against the bed and for flexing the edges of the facing material, and folding mechanism co-acting with the bed and adapted to be presented 20 against the flexed edges of the facing material to fold the same over and against the opposite side of the stiffening material, said mechanism including a pair of slidably arranged side members and a pair of slidably 25 arranged end members, crank shafts having their cranks connected with said side and end members and means for rotating said shafts.

4. An apparatus of the class described comprising a bed, means thereon for holding 30 the stiffening material and the facing material with the edges of the facing material bent at right angles around the edges of the stiffening material, a supporting member, means for moving the bed to a point adjacent 35 said supporting member and folding mechanism carried by said supporting member for folding the edges of the facing material over the opposite face of the stiffening material, said folding mechanism comprising 40 slidably mounted side and end strips, crank shafts for sliding said strips, and means for rotating the shafts.

5. An apparatus of the class described comprising a bed, means thereon for holding 45 the two sheets of material and a supporting plate, folding mechanism on said plate, a spring plunger on the bed, a plunger on the supporting plate and means for operating the last mentioned plunger to form the knob- 50 receiving opening in the sheets of materials.

In testimony whereof we affix our signatures.

ATTILIO BIANCHI.
JOHN OCCHIPINTI.
